UNITED STATES PATENT OFFICE.

GEORGE D. SMITH, OF PATERSON, NEW JERSEY.

PAPER RECEPTACLE.

1,092,868.

Specification of Letters Patent.

Patented Apr. 14, 1914.

Application filed October 24, 1913. Serial No. 797,047.

To all whom it may concern:

Be it known that I, GEORGE D. SMITH, a citizen of the United States, residing at Paterson, in the county of Passaic and State 5 of New Jersey, have invented certain new and useful Improvements in Paper Receptacles, of which the following is a specification.

This invention relates to the manufacture 10 of paper receptacles and the like and it has for its object to provide, at a minimum cost, a paper receptacle that may be vended in the folded state and readily opened by the user into condition to receive its contents, 15 the same being self-adapted to retain its receptacle forming shape when once expanded thereto.

According to this invention I fold a collapsed paper sack having two opposite 20 equal-width flat or plain sides and two opposite equal-width infolded bellows sides at least twice across the same, the folds being spaced apart a distance equaling the width of each folded bellows side, thus forming in 25 each layer of each bellows side between said folds a square. Upon holding the sack below and adjoining the relatively lower fold and expanding the part thereof above such fold until each bellows side is extended to 30 its limit with respect to the part thereof above the upper fold each of the two square-shaped layers forming the part thereof below such fold and above the relatively lower fold may be folded on a diagonal extending 35 from the upper outer to the lower inner corner of the square, thus producing a receptacle whose sides are rectangularly disposed and whose bottom (including in part 40 portions of the plain sides of the sack which are between said folds and in part the folded squares) is substantially flat.

I have illustrated my invention in the accompanying drawings by views showing the paper receptacle in various stages from the 45 beginning to the completion of its formation, Figure 1 being a plan view of a collapsed paper sack of a well-known type; Fig. 2 a perspective view of the sack after the first fold—having reference to the 50 preferred manner of forming the receptacle—has been formed; Fig. 3 shows the sack after the second fold has been formed; Fig. 4 shows the sack after the third fold has been formed and in the condition in 55 which it will usually be vended; Fig. 5 shows the sack during the operation of

shaping its upper part to form the receptacle; and, Fig. 6 is a plan view and Fig. 7 a perspective view of the completed receptacle.

Having a sack (Fig. 1) of paper or other 60 suitably stiff flexible material and provided with two equal-width and rectangular opposite flat or plain sides *a* and *b* and two equal-width opposite infolded rectangular 65 bellows sides *c* and *d*, I fold the same at right angles to the longitudinal margins of its sides *a* and *b* on first the line *e* disposed (for a purpose which will appear) a distance from the bottom *A* of the sack that is equal 70 to twice the width of each folded bellows side (Fig. 2). The sack is then folded on a line *f* which is parallel with line *e* and spaced therefrom a distance equal to the 75 width of each folded bellows side, this fold being then straightened out, leaving simply a crease. The sack is then folded on the line *g*, parallel with lines *e* and *f* and distanced from line *f* the width of the folded bellows sides, the fold in this case being 80 preferably the reverse of the fold *e*. Fig. 3 shows the sack after folds *f* and *g*, respectively, have been formed therein, the packet shown in Fig. 4 being the form in which my improved article of manufacture will usually be vended.

In view of the foregoing it will be seen that each of the two bellows sides will have two squares (one in each of its two layers) formed by its outer and inner margins and 85 the folds *f* and *g*.

To form the receptacle the user places the part of the sack below the fold *f* upon a flat surface and holding the sack with one hand placed thereon relatively below and adjoining said fold *f* opens or expands the mouth of the sack with his other hand to a limit afforded by the full extension of each bellows side. In the accomplishment of this the upper inner corner *h* of each of the foregoing 90 squares will be brought into coincidence (or substantially so) with its lower outer corner *i*, the square folding on its diagonal *j*; upon creasing down each fold thus produced the receptacle produced, which is substantially perfectly rectangular and has its bottom composed in part of the portions of the sides *a* and *b* of the sack that are between the folds *f* and *g* and in part of the folded 95 squares, will be self-adapted to maintain its 100 shape.

When the receptacle has been used and is

to be destroyed with its contents the latter are first allowed to fall into the reserve space which exists in the sack below the part that forms the receptacle as soon as the sack is extended or opened to its full capacity, thus eliminating the folds *e* and *f*, whereupon the upper part of the sack may be folded upon itself one or more times or if desired sealed in some way.

10 My improved article of manufacture may be used for various purposes, although it has been specially designed for sanitary uses.

15 It will be apparent that by spacing the folds *e*, *f* and *g* in the way herein described I accomplish both the forming of the squares and the folding of the sack into a convenient shape for vending (Fig. 4).

Having thus fully described my invention, 20 what I claim and desire to secure by Letters Patent is:

25 As an article of manufacture, a sack formed of suitably stiff flexible material having two opposite equal-width plain rectangular sides and two opposite equal-width

infolded rectangular bellows sides, said sack being folded in the collapsed state twice transversely thereof on lines at right angles to the longitudinal margins of the plain sides and spaced apart a distance equaling 30 the width of each folded bellows side, whereby to produce between said folds a square in each layer of each folded bellows side and, upon holding the material of the sack relatively below and adjoining the relatively 35 lower fold and expanding the part of the sack thereabove sufficiently to substantially extend each bellows side to its limit, to permit the two squares in each bellows side to be folded on diagonals thereof extending 40 from their relatively upper outer to their lower inner corners and thus produce and maintain a receptacle in the upper portion of the sack.

In testimony whereof I affix my signature 45 in presence of two witnesses.

GEORGE D. SMITH.
